UNITED STATES PATENT OFFICE.

PRIM GAGNON, OF HAMMOND, INDIANA.

RAIL-LIFTING TOOL.

1,131,051.

Specification of Letters Patent. Patented Mar. 9, 1915.

Application filed August 27, 1914. Serial No. 858,945.

To all whom it may concern:

Be it known that I, PRIM GAGNON, a citizen of the United States, residing at Hammond, in the county of Lake and State of Indiana, have invented certain new and useful Improvements in Rail-Lifting Tools; and I do declare the following to be a full, clear, and exact description of the invention, such as will enable others skilled in the art 10 to which it appertains to make and use the same.

My invention relates broadly to lifting tools and more particularly to those designed for the purpose of raising and carrying 15 railway rails.

The main object of the invention is to provide a tool which may be quickly and easily applied to or removed from the head of a rail and to so construct the same as to 20 allow for its use by a single person. By so constructing the device, each workman may carry a separate tool whereas, with the usual tongs now employed for the purpose of transporting rails, it is necessary for two 25 men to carry such tongs from place to place.

In carrying out the above end, I have provided a substantially L-shaped rail gripping member having inturned noses on both of its ends and an angular handle for operating 30 the device.

A further object of the invention becomes to provide means whereby the two arms of the L-shaped member may be adjusted to render the device applicable to rails of different 35 sizes.

Yet another object is to so form the tool as to adjust one arm of the L-shaped member both laterally and vertically at the same time.

With the above and minor objects in view, the invention resides in certain novel features of construction and combination herein described and claimed and shown in the drawings wherein;

Figure 1 is a side elevation of my improved lifting tool applied to use; Fig. 2 is an edge view of the tool proper, the handle being broken away; Fig. 3 is a vertical longitudinal section through the head of the tool showing its application to a rail having a larger head than that illustrated in Fig. 1; and Fig. 4 is a horizontal section taken on the line 4—4 of Fig. 1.

In the accompanying drawings I have shown my improved rail lifting tool as comprising an upright rigid jaw 1, having an

inturned nose 2 at its lower end while its upper end is provided with a laterally extending arm 3 whose free end is bent downwardly as indicated at 4, the arm 3 overlying the nose 2 and being spaced at suitable distance therefrom. As clearly seen in Figs. 1 and 3, the lower side of the arm 3 inclines upwardly and outwardly from its juncture with the jaw 1, this inclination being indicated by the numeral 5. Directly beneath the arm 3 and having an inclined upper surface 6 contacting with the inclined lower surface 5 thereof, is an adjustable jaw 7, whose outer end is provided with a downwardly turned nose 8, the jaw 7 being rendered adjustable by an upright bolt 9 whose head is countersunk in the lower side of said jaw, said bolt rising through a slot 10 in the arm 3 and receiving on its upper end a washer 11 and a clamping nut 12. The outer end of the jaw 7 and its nose 8 are shaped to snugly contact with the inner side of the downwardly turned end 4 of the jaw 3 when the parts stand as seen in Fig. 3 for application to a comparatively large rail R, the portion 4 thereby effectually bracing the jaw 7 and positively locking the same against outward movement.

When the device is applied to a comparatively small rail R' as seen in Fig. 1, the jaw 7 is adjusted inwardly as seen in this figure. During this inward adjustment, the inclined surfaces 5 and 6 will cause the jaw 7 to move downwardly at the same time it is being adjusted inwardly, thereby positioning the parts in such a manner as to allow the same to properly engage the head of a rail whether the same be small or large.

The upright rigid jaw 1 is here shown as provided with an upright attaching shank 13 to which the upright lower end 14 of an L-shaped handle 15 is secured by bolts 16 or other appropriate fastening devices. It will therefore be seen that it is necessary to rock the tool by its handle 15 in order to apply the same to a rail or to remove it therefrom. In order to allow the rail to be more rigidly clamped within the tool, the inner side of the nose 8 is preferably inclined downwardly and outwardly as indicated at 8'.

From the foregoing description, taken in connection with the accompanying drawings, it will be seen that an extremely simple lifting tool has been provided, yet one which will be strong and efficient in operation.

I may here explain that the term "L-shaped member," appearing in the claims, applies to the rigid jaw 1 and the movable jaw 7, since these two members constitute a substantially L-shaped formation.

Having thus described my invention, what I claim as new and desire to secure by Letters-Patent is:

1. A rail lifting tool comprising an upright rigid jaw having a laterally extending nose on its lower end, a rigid arm spaced from said nose and projecting laterally from the upper end of said rigid jaw, a substantially L-shaped movable jaw beneath said arm, means whereby said L-shaped jaw may be locked in contact with said arm, and an operating handle projecting laterally from the rigid jaw.
2. A rail lifting tool comprising an upright rigid jaw having a laterally turned nose on its lower end, an arm projecting laterally from the upper end of said jaw and overlying said nose, the lower face of said arm inclining upwardly and outwardly from its juncture with said rigid jaw, a substantially L-shaped movable jaw beneath said arm and having an inclined upper surface contacting with the inclined surface thereof, means whereby said movable jaw may be locked in adjusted position and an operating handle projecting laterally from the rigid jaw.
3. A rail lifting tool comprising an upright rigid jaw having a laterally turned nose on its lower end, a slotted arm projecting laterally from the upper end of said rigid jaw and overlying said nose, a substantially L-shaped movable jaw beneath said arm and contacting therewith, an adjusting bolt passing through said movable jaw and through a slot in said arm, and an operating handle projecting laterally from the rigid jaw.
4. A rail lifting tool comprising an up-

right rigid jaw having a laterally turned nose on its lower end, a slotted arm projecting laterally from the upper end of said rigid jaw and overlying said nose, said arm having its lower surface inclined upwardly and outwardly from its juncture with said rigid jaw, a substantially L-shaped movable jaw beneath said arm and having an inclined upper surface contacting with the inclined lower surface thereof, an adjusting bolt passing through said movable jaw and through the slot in said arm, and an operating handle projecting laterally from the rigid jaw.

5. A rail lifting tool comprising an upright rigid jaw having a laterally turned nose on its lower end, an arm projecting laterally from the upper end of said jaw and overlying said nose, said arm having its free end bent downwardly to form a stop, a substantially L-shaped movable jaw beneath said arm and designed to be limited in its outward movement by said stop, means for locking said movable jaw in adjusted position, and an operating handle projecting laterally from said rigid jaw.

6. A rail lifting tool comprising an upright rigid jaw having a laterally turned nose on its lower end, a movable jaw projecting laterally from the upper end of said rigid jaw and spaced above the nose thereon, said movable jaw having a downturned nose at its free end, means whereby said movable jaw may be simultaneously adjusted both horizontally and vertically, and a handle for said tool.

In testimony whereof I have hereunto set my hand in presence of two subscribing witnesses.

PRIM GAGNON.
